COIN SELECTOR

Bert E. Mills, Oak Park, Ill., assignor to Mills Novelty Company, Chicago, Ill., a corporation of Illinois

Application October 1, 1937, Serial No. 166,764

3 Claims. (Cl. 194—100)

This invention relates to coin-selecting devices of the type adapted to test the material of the coin and to reject all coins and slugs except those of the proper material, the device providing for separation of the coins by the combined actions of a field of magnetic flux intersecting the trajectory of an inserted coin and a member adapted to cause rebound of such coin.

While the use of the magnetic field and an anvil against which the coin may rebound is not new in the coin-selection art, the present invention improves upon prior devices of this kind by employing instead of the conventional rebound anvil with flat face, a member which constitutes a combination of a rebound member and a separating barrier, and which presents a surface of such character for contact by the coin that a very slight deviation in the angle of approach or point of contact of the coin with said member will result in a relatively great divergence in the trajectory of the coin after leaving the rebound member. (In using the term "rebound member," herein, it will be understood I am referring at all times to a device having the combined functions of a rebound anvil and a separating barrier, the shorter term being used for the sake of convenience.)

The invention has as one of its objects to provide a selector which will efficiently select silver coins from all other coins and slugs. To attain this result with certainty constitutes a problem in view of the fact that the electrical conductivity of silver and copper are so nearly the same that passing them through a magnetic field produces only a slight divergence between their trajectories. Accordingly it is obvious that while it is not difficult to separate copper and silver coins from nickels in a nickel selecting chute, it is a distinctly difficult problem to separate copper slugs from silver coins in a silver selecting coin chute, where the slugs are the same size as the coins.

The present invention makes use, however, of the slight divergence which it is possible to create by passing silver and copper coins of identical size through a magnetic field, and efficiently separates such coins by greatly amplifying such divergence as the coins pass from the rebound member.

This is accomplished by employing a rebound member presenting a rounded surface for contact by the coins after they have been slightly diverged by passing through the magnetic field, the said surface being curved on a relatively small radius and being positioned relative to the respective coin trajectories so that one of the

coins will strike the rebound member almost on center but slightly to one side thereof and thence will rebound a substantial distance to that side, while the other will strike said rounded surface glancingly, because its point of contact is further offset on that side, and will merely be deflected slightly to that side and thereby definitely separated from the squarely bouncing coins. Coins and slugs of low conductivity, such as nickel, brass, lead, etc., will have sufficient divergence from the trajectories of the copper and silver coins so that they will either contact the rebound member on its other side, or completely clear said other side.

Another and important object of the invention is to provide simple and effective means for adjusting the relative position of the magnets employed for creating the field of magnetic flux through which the coins pass, thereby providing for accurate control of the trajectories of the coins and slugs under varying conditions affecting the device.

Other objects of the invention will become apparent from the following detailed description of the invention when considered in connection with the accompanying drawings, in which:

Figure 1 is a front elevation of a selector embodying the invention;

Figure 2 is a vertical, transverse, sectional view of the same, taken on the line 2—2 of Figure 1;

Figure 3 is a view similar to Figure 1, parts being removed and shown in section to illustrate the interior construction;

Figure 4 is a horizontal, transverse, sectional view, taken on the line 4—4 of Figure 3;

Figure 5 is a detailed sectional view, taken on the line 5—5 of Figure 1;

Figure 6 is a detailed sectional view, taken on the line 6—6 of Figure 1; and

Figure 7 is a cross-sectional view through a modified form of the rebound member.

A typical coin selector constructed in accordance with this invention comprises a base plate 10 which carries the various members forming a tortuous series of passages through which the coins travel. From the lower end of an inlet passage 11, a passage 12 extends laterally and downwardly. In the passage 12, undersized and ferrous coins and slugs are eliminated, as will be more fully set forth hereinafter. From the lower end of a block 13, forming the bottom of the passage 12, non-ferrous coins of proper size, indicated at C, will jump across the gap forming the inlet of scavenger passage 14 following the trajectory indicated by broken line 15, and will

bounce from dividing barrier 16, following trajectory 17, into passage 18 extending downwardly.

Rotating in clockwise direction, as a result of rolling down the upper edge of block 13, the coin will strike the upper edge of block 19, forming the bottom of a delivery passage 20, and as a result of such rotation will tend to roll uphill on the block 19, but will be stopped by a flange 21' which forms the outer side of passage 18. From this momentarily still position, the coin will commence to roll down the inclined delivery passage 20. In order to secure this result, the passages 18 and 20 form a return bend with respect to the passage 12.

At the lower end of the delivery passage 20, the coin rolls through a field of magnetic flux created between the opposed poles of horseshoe magnets 21 mounted on either side of the passage. Immediately thereafter, the coins will jump from the end 22 of the block 19 and will thence follow trajectories which diverge as a result of the varying effect of passage through said field.

As the coins pass through the magnetic field, those of nickel, brass, lead, and other material of low conductivity will be relatively unaffected thereby and will consequently follow trajectories indicated by the broken lines 23 and 23a. In doing so, they will either completely clear or will glancingly contact the far side of a rebound member 24, thence passing out of the selector through a discharge outlet 25. Coins of silver will be retarded by the resistance caused by eddy currents created within the coins by the cutting of the magnetic lines of force, and will consequently follow a much shorter trajectory, as indicated by the broken line 26. The rebound member 24 is positioned so that these coins will contact said member almost on top center, but slightly to the near side thereof (i. e., the side toward the line of approach of the coins).

The silver coins thus striking the rebound member squarely will rebound in a trajectory indicated by the broken line 27 to a distance sufficiently removed horizontally from the member 24 so that such coins will pass over a barrier 28 and out through a discharge passage 29 defined by the barrier 28 on one side and a bar 63' on the other. These coins are indicated in dotted lines by the reference numeral 63.

Copper coins, having even greater conductivity than silver, will be retarded even more than the silver coins by the action of the magnetic field, following a trajectory indicated by the broken line 30. Since the difference between the retardation of these coins and that of silver is very slight, these coins will strike the rebound member very close to the point of contact of the silver coins, but slightly more to the near side of the rebound member than that of the silver coins.

Owing to the curvature of the rebound member, this slight divergence between the points of contact will allow the copper coins to glance away from the rebound member on a trajectory 31 which is sufficiently divergent from the trajectory 27 so that the copper coins may pass through an intermediate outlet 32 located between the outlet 29 and the rebound member 24.

The rebound member 24 may be either in the form of a rigid pin mounted in the plate 10, as shown in Figure 3, or it may be a block 24a having a rounded upper edge 24b, as shown in Figure 7.

The inlet passage 11 is formed between a thin, spring-metal, rear plate 33 (Figures 1 and 2), a pair of spaced side bars 34 (Figure 3), and a front plate 35 to which is secured the scavenger gate 36. Said plates are normally positioned to dispose the inlet passage 11 in the plane of the upper lateral coin passage 12 (Figure 1), being held in this position by means of cams 37 formed on a shaft 38 which is journaled in brackets 39 secured to the plate 10. The plates 33 and 35 are attached at their upper ends by means of a clamping strip 40 and screws 41, to a bracket 42 (Figure 2), forming an upward continuation of the plate 10. Both plates are formed so as to tend to spring outwardly away from the plate 10. When a scavenger control lever 43 is moved upwardly, rotating the shaft 38 against the pull of a spring 44, the plates 33 and 35 will swing outwardly away from the plate 10, the rear plate 33 sweeping from the upper edge of the block 13, any ferrous slugs which may have been arrested by a horseshoe magnet 45 mounted on the rear side of the plate 10 behind the passage 12.

Likewise, the rear plate 33 will sweep from the passage 12 any bent coins or slugs which have otherwise become lodged in the passages 11 or 16. The forward plate 35, at its outer limit of movement, will separate slightly from the plate 33, the latter being detained by engaging a stop 46 on the block 13.

Coins and slugs thus released will fall, as indicated by broken line 65, into a scavenger chute 47, the outer wall of which is flared outwardly at the top beyond the plane of the passages 11 and 12, the scavenger passage 14 being a continuation of said chute. The bottom of the passage 14 is formed by a block 48 secured to the plate 10 by means of screws 49.

Those ferrous coins which have been merely slowed down by the magnet 45, and pass beyond the end of the block 13, may enter the scavenger passage 14 at its upper end communicating with passage 12. The scavenger passage 14 and chute 47 communicate with a vertical scavenger passage 50, formed between a depending leg 51 of the scavenger chute 47, the plate 10, the end of the block 48, and a flange 52 of the leg 51.

The small coin-eliminating device comprises a gate member 80, having a bell crank arm 81 pivoted at 82 on the plate 13, and a pawl 83 pivoted at 84 on the end of the arm 81 and normally hanging over a notch 85 in the scavenger gate 36 so that as the gate 80 is swung forwardly by an undersized coin clearing the pawl 83, said pawl will engage and lock in the notch 85 before the coin has cleared the gate 80, whereupon the coin will be restrained from further movement. A proper-sized coin, however, will engage the pawl 83 and swing it laterally sufficiently to clear the notch 85 and the end of the scavenger gate 36 so that the gate 80 may swing clear of the coin.

The passage 18 is formed between the block 16, the block 19, the plate 10, and a cover member 56 secured at 54 to the plate 10 and at 55 to the block 19. The lower portion 53 of the cover 56 cooperates with the blocks 16, 19, and 48 and the plate 10 to form the passage 20.

The magnets 21 are encased in non-magnetic casings 57 having flanges 58 which are secured by screws 59 threaded into the block 48. The plate 10 is provided with an opening 60 to receive the flange 58 of one of the casings 57.

The screws 59 (Figure 5) pass freely through openings 59' in the flange 58 of one of the casings 57, and said casing is urged toward the block 48

by coil springs 61 encircling the shanks of the screws 59 and compressed between the heads thereof and said flange 58.

This yielding connection allows one magnet 21 to be adjusted relative to the plate 10 and to the other magnet so as to vary the intensity of the magnetic flux. The adjustment of this magnet is effected by means of an adjusting screw 62 (Figure 6), which is threaded through the flange 58 and engages against the block 48. The other horseshoe magnet is permanently positioned by the engagement of the flange 58 of its casing by the threaded ends of the screws 59. By means of this adjustment, the trajectories of the coins and slugs can be accurately controlled and any loss in intensity in the field of magnetic flux can be readily compensated for simply by the adjusting screw.

The foregoing detailed description has been given for clearness of understanding only, and no unnecessary limitations should be understood therefrom, but the appended claims should be construed as broadly as permissible in view of the prior art.

I claim as my invention:

1. In a coin selector, means, including a vertical wall, forming a passage for coins, a magnet disposed outside said wall with its poles arranged adjacent to said passage, resilient means acting on the magnet for urging the poles thereof toward said passage, and adjustable means reacting on a fixed abutment for moving said magnet against the force exerted by said resilient means to vary

the effect of the magnet poles upon coins travelling through said passage.

2. In a coin selector, means, including a vertical wall, forming a passage for coins, a magnet disposed outside said wall with its poles arranged in association with said passage, means attaching one side of said magnet to said wall so as to allow tilting movement of the magnet around an axis parallel to the wall, means attaching an opposite side of the magnet to and resiliently urging it toward the wall, and a set screw threadedly connected to the magnet and abutting the wall adjacent said resilient attaching means, for adjusting the poles of the magnet toward and away from said passage.

3. In a coin selector, means, including a vertical wall, forming a passage for coins, a magnet mounted on one side of said passage, means supporting said magnet for tiltable movement around an axis parallel with said wall so as to allow adjustment of the magnet poles toward and away from said passage, an adjusting screw operative upon said magnet whereby said magnet may be positioned with its poles at a greater or less distance from said passage to vary the magnetic flux acting upon coins travelling through said passage, and means resiliently urging said magnet toward said passage and opposing the action of the adjusting screw, said screw, when in any adjusted position, holding the poles of said magnet positively against movement toward coins in said passage.

BERT E. MILLS.
